UNITED STATES PATENT OFFICE.

GEORGE A. PARKER, OF BROCKTON, MASSACHUSETTS.

FEEDING DEVICE FOR TACK-MAKING MACHINES.

Application filed July 14, 1921. Serial No. 484,677.

To all whom it may concern:

Be it known that I, GEORGE A. PARKER, a citizen of the United States, resident of Brockton, in the county of Plymouth and 5 State of Massachusetts, have made a certain new and useful Invention in Feeding Devices for Tack-Making Machines; and I declare the following to be a full, clear, and exact description of the same, such as will 10 enable others skilled in the art to which it appertains to make and use the invention, reference being had to the accompanying drawings, and to letters or figures of reference marked thereon, which form a part of this 15 specification.

My invention relates to an improvement in blank feeding mechanism for tack machines.

In making tacks and similar articles it is 20 customary to provide mechanism for feeding blanks of sheet metal to the cutting machines, and the feeders are so made as to advance the blanks out of the delivery end of the device and to the cutters at a certain 25 speed.

So far as I am aware, however, the machines constructed heretofore are adapted to hold and work on but one blank at a time, necessitating the constant attention of the 30 operator, and are also open to the objection that the rate of feed is fixed and cannot be varied.

It is an object of my invention to provide a machine capable of containing a plurality 35 of blanks, which are fed out automatically one after another.

It is a further object of my invention to provide a device of this character with novel feeding means, which can be adjusted to 40 materially vary the rate of feed of the blanks.

In carrying out my invention I provide a rotatable blank carrying element, and means, actuated by the rotation of said element, for imparting a step by step feed to the blanks in said element, and which feed may be varied at will.

In the accompanying drawings:

Figure 1 is a side elevation of the blank 50 feeding device,

Figure 2 is a vertical section therethrough showing a blank and the feeding mechanism,

Figure 3 is a horizontal section through the device,

55 Figure 4 is a section on the line 4—4, Figure 2.

Figure 5 is a section taken on line 5—5 of Figure 2,

Figure 6 is a section taken on line 6—6 of Figure 2,

Figure 7 is a detailed sectional view of the delivery end of the device,

Figure 8 is a section on line 8—8 of Figure 2,

Figure 9 is a section on line 9—9 of Figure 7 showing the rollers for supporting and delivering a blank, and,

Figure 10 is a perspective partially broken away, of the sprocket chain and lugs for feeding the blanks.

Figure 11 is a side view of the delivery end of the device, with a blank fed to the cutting die.

Figure 12 is an end view of the delivery end of the device.

Figure 13 is a face view of an end feed roller with its spring.

The stationary cylinder or housing 1 is supported on legs 2, and at one end is closed by the collar 3 having an axial opening 4 and a pair of recesses 5 disposed on opposite sides of the axial opening. The collar 3 supports a plate or washer 6 carrying brackets 7 in which the cam elements 8 are supported. The cams are adjustable longitudinally in 85 the recesses 5, and are controlled by some such means as nuts 9.

Rotatably mounted in the axial opening 4 of the collar 3, is a flanged journal 10, provided with a longitudinal slot 11 through 90 which blank 12 passes. The flange 13 of the journal bears against the inner face of the collar 3 and is provided with oppositely disposed peripheral recesses 14, and bearings 15 opening therein. Journaled in the bearings 15 on pins 16, the sprocket gears 17, and ratchet gear 18, are mounted, to rotate with the journal 10.

The cam actuated ratchets and pawls 19 are pivoted on pins 16, and are provided 100 with rollers which ride over the stationary cams 8, as the journal 10 rotates, carrying with it the sprocket and ratchet gears 17 and 18. As each roller 20 rides up on a cam 8 the pawl 19 will move the ratchet gear forward, and as the roller drops off the cam, the pawl will be retracted and will engage behind the next tooth ready for engagement with the next cam 8. It will be seen that as the cams are adjusted longitudinally toward the rollers, the rollers will be raised higher, and will consequently advance the ratchet.

gear and associated sprocket gear a greater distance.

Rigidly affixed to the inner end of the journal 10 is a tube or cylinder 21 terminating in a flared collar 22 rotatably mounted in the end of the stationary tube 1. The flared collar 22 also has peripheral openings in which sprocket gears 17 are journaled, over which and sprocket gears 17, the 10 sprocket chains 28 pass. The chains may be of any construction, but each link of one half of each chain only carries a lug 29 for engagement behind a blank for feeding it from the machine. At intervals in the tube 15 21 hollow partitions 23 are fastened, provided with rectangular axial openings and carrying spring-pressed blank-holding fingers 24 pivoted on pins 25 mounted in the partitions.

20 The blank magazine comprising two similar U-shaped members 26 with a longitudinal slot between them, has spaces 27 through which the spring fingers 24 extend at the forward end of the machine, and affixed to 25 the rotatable journal 10 is a reduced cylinder 31, carrying rollers 32 for guiding the blanks from the machine. This rotation is obtained from any suitable source of power, through a gear 30 affixed to the journal 10.

30 The operation of the machine is as follows, after determining and fixing the rate of feed by adjusting the cams 8 to the proper position, the operator inserts blanks into the magazine 26—through the flared collar 22, 35 until the magazine is full, with the spring fingers pressing against the blanks and tending to force them toward the center. The machine is then started and as the movable cylinder and journal rotate, the sprocket 40 and chains will move with a step by step movement until the first link carrying a lug reaches the rear of the machine, here the lug enters the slot between the halves of the magazine and engages behind it and moves 45 it forward.

After it has been pushed as far as the lug can carry it, the lug will cease to engage the blank and will then pass over the sprocket and toward the rear of the machine, on the 50 outside of the rotating cylinder.

After all of the lug-carrying links have passed over the sprocket, there will be no lugs in the longitudinal slot of the magazine and the spring fingers will push another 55 blank in to the center in position to be engaged by the lug as it again enters the magazine. The second blank is already just behind the stub end of the first and so the end is fed out through the rollers 32 by the 60 second blank with but a momentary delay in the feeding.

It is believed the operation of the machine will be apparent, and it will be seen that I have produced a machine for feeding a plurality of blanks one after another without 65

the necessity of inserting a new blank as each previous one is expelled and which further has a positive feeding mechanism which can be adjusted as to speed by a very simple operation.

It is desirable to eject the stubs of the blanks left in the machine after the operation of the cutting dies, the accumulation of these stubs having heretofore given the operator much trouble.

To this end the cylinder 31 is attached to the journal 10 by diametrically opposite screws 33, allowing a slight deflection of said cylinder. The outermost pair of rollers 32 are mounted within an annulus 34, pivotally supported at 35 in extensions 36 of the cylinder 31, said annulus being held normally axially aligned with the cylinder by springs 37.

Each of the rollers 32 of the outermost 85 pair are provided with a coil spring 38, designed to be tensioned as the blank is fed through these rollers. When the blank has passed from engagement with the other rollers carried by the cylinder 31, and the 90 feed devices are in such position that said blank may lie flat upon the die face of the cutter, the tack machine is operated, thereby bringing the blank into horizontal position and rocking the cylinder 31 and annulus 34 95 upon the pivots 33 and 35. The butt of the blank is thus brought out of line with the head of the succeeding blank, and upon the cutting away of the body portion therefrom, will be ejected rearwardly by the reaction 100 of the springs 38.

I claim as my invention:

1. In a blank feeding mechanism, a rotatable blank holder, and means actuated by the rotation of said holder for feeding the 105 blanks, said means being adjustable so as to control the rate of speed of said blanks.

2. In a blank feeding mechanism, the combination with a rotary blank holding element, of an endless feeder carried by said element, and of stationarily mounted means controlling and actuating the endless feeder, said means comprising longitudinally adjustable tapered cams.

3. In a blank feeding mechanism, the combination with a stationary housing, journal and cylinder rotatably mounted in the housing, a blank magazine carried by the cylinder, and endless chains supported by the journal and cylinder, lugs on parts of said 115 chains adapted to extend into the magazine for feeding a blank therefrom, and means actuated by the rotation of the journal and cylinder for moving said chains, said means comprising a pair of adjustable cams mounted in the housing, and a pawl and ratchet mounted in the journal and actuating the chains.

4. In a blank feeding mechanism, a magazine, means for feeding the blanks succes- 120 125 130

sively from said magazine, and means acting reversely of said feed to eject the stubs.

5. In a blank feeding mechanism, a magazine, means for feeding the blanks successively from said magazine, and guide devices adapted to allow movement of a blank out of the line of feed.

In testimony whereof I affix my signature in presence of two witnesses.

GEORGE A. PARKER.
